PUMP MECHANISM

James E. McEvoy, Cleveland, Ohio, assignor to
Bailey Meter Company, a corporation of Delaware

Application October 9, 1948, Serial No. 53,671

14 Claims. (Cl. 230—74)

1

This invention relates to pump mechanisms, and more particularly to pump mechanisms that are adapted to deliver fluid at a constant volume rate from an intake connection to a discharge connection.

It is sometimes desirable that a pump mechanism be provided for pumping fluid at a constant volume rate from a source regardless of changes in back pressure of the discharge end and delivering it to a point of use in a uniform flow as long as the back pressure remains constant. Where the heating value of a gaseous fluid is to be measured on the basis of heat units per cubic foot of gas supplied from a source, it is necessary that some constant volume pump mechanism be employed. If the temperature and pressure of the gas at the point of supply are maintained constant, then a cubic foot of such gas will have a predetermined heat content. By providing a pump mechanism which delivers the gas at a constant volume rate from the source to the point of use, it is possible to determine readily the total heat value of the gas delivered. The pump mechanism should be so designed as to pump gas from the source at a constant volume rate even though the back pressure at its discharge end varies. It should also be capable of pumping at a constant volume rate for different densities of the fluid at the intake, and its rate of discharge to the point of use should also be constant.

An object of my invention is to provide an improved pump mechanism. Another object is to provide a pump mechanism that is adapted to deliver fluid at a constant volume rate from an intake connection to a discharge connection while the pressure in the latter either remains constant or varies within a predetermined range. Still another object is to provide a pump mechanism for pumping a continuous flow of gaseous fluid at a constant volume rate from a source under any given pressure and temperature conditions within predetermined limits. Yet another object is to provide an improved pump mechanism in which a volume of liquid is circulated in an enclosed path to discharge fluid from a supply connection to a discharge connection.

In the accompanying drawings there is shown for purposes of illustration one form which my invention may assume in practice.

In these drawings:

Fig. 1 is a perspective view of my improved pump mechanism.

Figs. 2 to 6 are perspective views of a single pump element of my improved mechanism in

2

various positions between the beginning and end of one complete cycle.

Referring to the drawings it will be noted that there is shown in Fig. 1 a pump mechanism generally designated 1 including a plurality of tubular pump elements 2, 3 and 4, each bent so that it completes one turn in the path of a helix. A plate 5 is attached to the ends of each element, as by welding, for closing the element and holding the ends in the proper relation relative to each other. The ends of each of the tubular elements are connected in communication with each other by a U-shaped tube 6 extending downwardly from the lower side of the element, as shown. The elements are held in spaced parallel relation relative to each other by connecting members 8, and a member 9 is shown connected to one of said elements at diametrically opposite points to act as a supporting frame for the connected pump elements. An elongated member 10 extends axially through the pump elements and is connected to the member 9 so as to support the elements in positions in which the radial distances from the elongated member to the elements are the same at all points along their lengths. At the lower end of the member 10 is a universal joint 12 connecting the member to a base plate 14. Mounted upon a standard 15 extending upwardly from the base plate is a motor 16 which is connected through a gear train 18 to a shaft 19 carrying a crank arm 20. The upper end of the elongated member 10 is connected to the crank arm so that it is moved in a circular path as the shaft 19 is rotated. The shaft 19 is so arranged that its axis is in alignment with the axis of the universal joint 12. It will be appreciated that by this arrangement the member 10 is always held tilted at a given angle relative to a horizontal plane, and a nutating motion of the pump mechanism is obtained as the upper end of the member 10 is swung in a circle by the crank arm. The lower portion of the universal joint 12 is held fixed relative to the base plate so as to prevent rotation of the member 10 on its own axis, and the upper end of the member 10 is loosely held by the crank arm to permit relative motion between them.

The pump elements are so arranged that the ends of each are spaced 120° from the ends of the others. Communicating with the ends of each pump element are intake and discharge conduits 22 and 23, the intake conduits being connected to a common conduit 25 and the discharge conduits being connected to a common conduit 26. As shown herein, the intake conduits are connected

to the upper ends of the pump elements while the discharge conduits are connected to their lower ends. The motor 16 is operated so that the member 10 is swung in a clockwise direction when looked at from above. The discharge ends of the pump elements are chamfered at 28 as shown for reasons that will be shortly described.

Contained within each of the pump elements is a volume of liquid 30, such as mercury, and, in a pump mechanism having three pump elements as shown, the volume of liquid is such as to fill each pump element throughout one-third of its length. In Fig. 2 the pump element 2 is shown in a position in which the liquid is beginning to uncover the intake conduit 22. At the discharge end of this element the liquid has moved a short distance into the discharge conduit 23 but the discharge fluid from the element ahead of the liquid volume was discontinued as soon as the liquid covered the end of the conduit. The cross sectional areas of the discharge conduits are made small enough so that the movement of the liquid into them has no appreciable effect on the discharge of fluid. As the element is moved from the position in Fig. 2 to the position of Fig. 3, the space within the element communicating with the intake is increased, and fluid to be pumped enters this space from the intake. In the position of Fig. 3 the discharge conduit is beginning to be uncovered so that fluid trapped within the element ahead of the liquid may be discharged. Movement of the element from the position of Fig. 3 toward the position of Fig. 4 results in a continued increase in the volume of the space at the intake and a decrease of the space at the discharge end ahead of the liquid volume. Before reaching the position of Fig. 4 the liquid will have moved completely out of the discharge end of the element into the U-tube 6. In Fig. 5 the element 2 has reached a position where the forward end of the liquid volume has covered the end of the discharge conduit, and the discharge of fluid is cut off. As the position changes to that of Fig. 6, liquid flows from the discharge end of the element through the U-tube 6 to the intake end, and, in the position of Fig. 6, the end of the intake conduit is covered to trap the fluid admitted to the element. In all positions of the pump element the U-tube is substantially filled with liquid so as to cut off communication between the intake and discharge ends.

If the intake and discharge pressures are the same, the liquid will stand in the discharge conduit when in the position of Fig. 2 at the same level as it does at other points in the element 2. If the discharge pressure is higher than the intake pressure, the liquid will be forced back in the discharge conduit to a lower level. By making the discharge conduit of small cross sectional area, a forcing of the liquid from this conduit to the element will have practically no effect on the level of the liquid in the latter. If the pump element was made so that its discharge end was of the same shape as its intake end and was in alignment therewith, then the level of the liquid would be at the entrance to the discharge conduit when the element was in the position of Fig. 2 and the intake and discharge pressures were equal. Any increase in the discharge pressure would result in a forcing of the liquid to a lower level in the discharge end of the element. The volume of the liquid displaced would be considerable and would cause an appreciable increase in the level of the liquid at other points

in the element. This would mean that the beginning of the intake period would be delayed and the space within which fluid could be trapped would be smaller. The volume of the fluid pumped would drop off rapidly with increase in discharge pressure. Locating the end of the discharge conduit at a lower level than the intake by dropping the discharge end of the element and chamfering it, as shown, provides for an appreciable change in liquid level at the discharge by changes in back pressure without affecting the liquid level at other points except by the small amount of liquid displaced from the discharge conduit. This has no noticeable effects on the volume of fluid pumped.

The chamfering of the pump element at its discharge end produces another important affect on the operation of the pump mechanism. As the volume of liquid moves through the pump element its forward end lies in a plane cutting the element at an angle as shown in Figs. 2 to 6. When the forward end of the liquid volume reaches the discharge end of the element, it first contacts the closed end at the lower side of the element. If the discharge end was circular, then there would be a considerable space above the forward face of the liquid filled with fluid that was being pumped. As the position of the element continued to change, the liquid would move up into this space and force the fluid therein into the discharge conduit. It will be appreciated that the rate of fluid discharge would drop continuously from the time the liquid engages the lower edge of the closed end until the end of the element was completely filled with liquid. By chamfering the discharge end so that its shape is the same as that of the forward end of the liquid volume, then the discharge end of the element is filled completely by the liquid as soon as the liquid reaches this end. The pumped fluid is completely discharged from the pump element at this instant, and the rate of fluid discharge is uniform during the full period of discharge.

Since each of the pump elements is only one-third filled by the liquid volume then two-thirds of the space in the element is filled with fluid to be pumped, and discharge of this fluid takes place while the volume of liquid moves through an angle of 240°. With the ends of each element spaced 120° from the ends of the other elements, there are always two elements discharging. It will be appreciated that the pump mechanism may be provided with more or less than three pump elements, if desired. With a pump having only two elements, the ends of one element would be located 180° from the ends of the other, and each would be half filled with liquid. In this case only one element would be discharging fluid at a time. Just as the discharge was cut off in one of the elements, the other element would be starting to discharge. By adding only one more element, the output of the pump is doubled. If four pump elements were used, they would be arranged so that the points of intake and discharge were spaced 90° apart, and each element would be $\frac{1}{4}$ filled with liquid. With this arrangement three elements would be discharging fluid at all times. For each element added the output is increased by the amount of discharge from one more element. The spacing of the points of intake and discharge and the volume of the liquid used are varied inversely with the number of pump elements.

As a result of my invention there is provided a pump mechanism which takes fluid at a con-

stant volume rate from an intake connection and delivers it to a discharge connection. If the conditions at the point of intake remain constant, then there is delivered at the discharge a quantity of fluid of known value. With the structure of my pump mechanism as shown and described, a variation of the pressure at the discharge end has no appreciable affect on the volume of fluid received at the intake, and the discharge is continuous and at a uniform rate. While the pump mechanism is shown pumping a gaseous fluid it will be understood that it may be used as well to pump a liquid provided that the pumped liquid is lighter than the liquid circulated in the elements to produce the pumping action.

While there is described in this application one form which my invention may assume in practice it will be understood that it may be modified and embodied in various forms without departing from the spirit and the scope of the appended claims.

What I claim as new and desire to secure by Letters Patent of the United States, is:

1. A pump mechanism comprising, in combination, a tubular element conforming to the shape of a helix and extending through an angle of 360°, means for closing the ends of said element, passage means for connecting the ends of said element in communication with each other, a volume of liquid partially filling said element, an intake conduit communicating with one end of said element, a discharge conduit communicating with the other end of said element, and means for producing a nutating motion of said element about a vertical axis.

2. The pump mechanism of claim 1 in which said intake conduit communicates with the upper end of said element, and said last mentioned means produces a nutating motion progressing from the intake and along the element toward the discharge end.

3. The pump mechanism of claim 1 in which said passage means comprises a U-tube extending downwardly from the element and having its legs communicating with said ends at a low point on their sides, said intake conduit communicates with the more elevated end of said element, and said last mentioned means produces a nutating motion progressing from the intake end along the element toward the discharge end.

4. A pump mechanism comprising, in combination, a tubular element conforming to the shape of a helix and extending through an angle of 360°, means for closing the ends of said element, a chamfered portion at the lower of the ends of said element providing a space conforming to the shape of the end of a liquid volume moving within said element immediately prior to contact between the two, a volume of liquid partially filling said element, passage means for connecting the ends of said element in communication with each other, an intake conduit communicating with one end of said element, a discharge conduit communicating with the other end of said element, and means for producing a nutating motion of said element about a vertical axis.

5. The pump mechanism of claim 4 in which said intake conduit is connected to the upper end of said element, said discharge conduit is connected to the lower end of said element through the upper surface of said chamfered portion, and said last mentioned means produces a nutating motion progressing from the intake end along the element toward the discharge end.

6. A pump mechanism comprising, in combi-

nation, a plurality of tubular elements, each conforming to the shape of a helix and extending through an angle of 360°, means for closing the ends of said elements, means connecting said elements together in spaced axial alignment and with their ends spaced equal angular distances apart, passage means connecting the ends of each of said elements in communication with each other, a volume of liquid partially filling each of said elements, intake conduits communicating with a common source and connected to one end of each of said elements, discharge conduits communicating with a common point of use and connected to the other end of each of said elements, and means for producing a nutating motion of said connected elements about a vertical axis.

7. The pump mechanism of claim 6 in which said intake conduits communicate with the more elevated of the ends of said elements, said discharge conduits communicate with the lower ends of said elements, and said last mentioned means produces a nutating motion progressing from said upper ends toward said lower ends.

8. A pump mechanism comprising, in combination, a plurality of tubular elements, each conforming to the shape of a helix and extending through an angle of 360°, said elements being spaced along a common central axis, means for closing the ends of said elements, a chamfered portion at the lower end of each of said elements providing a space conforming to the shape of an end of a liquid volume moving within the element immediately prior to contact between the two, a liquid volume partially filling each of said elements, passage means connecting the ends of each of said elements in communication with each other, means connecting said elements together in spaced axial alignment and with their ends spaced equal angular distances apart, intake conduits communicating with a common source and connected to the upper ends of said elements, discharge conduits communicating with a common point of use and connected to the lower ends of said elements through the upper surfaces of said chamfered portions, and means for producing a nutating motion of said connected elements about a vertical axis.

9. The pump mechanism of claim 8 in which said passage means comprises U-tubes connected to the ends of said elements at points on their lower sides and extending downwardly therefrom.

10. The pump mechanism of claim 8 in which said last mentioned means produces a nutating motion progressing from the intake toward the discharge ends of the elements.

11. The pump mechanism of claim 8 in which said last mentioned means comprises an elongated member extending axially through said connected elements, means connecting said elements to said member so that they are spaced radially equal distances therefrom at all points along their lengths, means supporting one end of said elongated member for pivotal movement in any direction, and means for swinging the other end of said member in a circular path whose center is in vertical alignment with said pivotal supporting means.

12. The pump mechanism of claim 8 in which the discharge conduits are of a small cross sectional area compared to the cross sectional area of said elements.

13. A pump mechanism comprising, in combination, three tubular elements, each conforming to the shape of a helix and extending through an angle of 360°, said elements being spaced along

a common central axis, means for closing the ends of said elements, a chamfered portion at the lower end of each of said elements providing a space conforming to the shape of an end of a liquid volume moving within the element immediately prior to contact between the two, a liquid volume filling each of said elements throughout one-third of its length, U-tubes connected to the ends of each of said elements at their lower sides and extending downwardly therefrom, means connecting said elements together in spaced axial alignment and with their ends spaced 120° apart, intake conduits communicating with a common source and connected to the upper ends of said elements, discharge conduits communicating with a common point of use and connected to the lower ends of said elements through the upper surfaces of said chamfered portions, and means for producing a nutating motion of said connected elements about a vertical axis.

14. A pump mechanism comprising, in combination, a plurality of tubular elements, each having its longitudinal axis lying in the surface of a cylinder and extending through an angle of 360°,

means for closing the ends of said elements, passage means for connecting the ends of each of said elements in communication, means connecting said elements in spaced axial alignment and with their ends spaced equal angular distances apart, a volume of liquid partially filling each of said elements, intake conduits communicating with a common source and connected to one end of each of said elements, discharge conduits leading to a common point of use and connected to the other end of each of said elements, and means for producing a nutating motion of said connected elements about a vertical axis.
